UNITED STATES PATENT OFFICE.

EDGAR H. MUMFORD, OF PLAINFIELD, NEW JERSEY.

JOLT RAMMING-MACHINE.

1,105,821.

Specification of Letters Patent. Patented Aug. 4, 1914.

Application filed March 9, 1914. Serial No. 823,413.

To all whom it may concern:

Be it known that I, EDGAR H. MUMFORD, a citizen of the United States, residing at Plainfield, in the county of Union and State 5 of New Jersey, have invented certain new and useful Improvements in Jolt Ramming-Machines, of which the following is a specification.

My invention relates to molding machines, 10 and has special reference to what are known as joiting or jarring machines for forming sand molds.

One of the primary objects of my invention is to provide a cheap, simple, and efficient form of controlling device to govern 15 the movement of such machines in their jolting operation, and one which will be automatic in operation and constructed of few and durable parts so that there will be practically no danger of said device getting out 20 of order.

The foregoing, together with such other objects as may hereinafter appear or are incident to my invention I attain by means of 25 a construction, a preferred embodiment of which I have shown in the accompanying drawings, wherein—

Figure 1 is a perspective view of a jolt ramming machine having applied thereto 30 my improved controlling device; Figs. 2 and 3 are sectional views drawn somewhat in diagrammatic character for purposes of illustration of the operation of the various parts, Fig. 3 showing the controlling device 35 in vertical instead of horizontal position.

Referring to the drawings, the numeral 7 indicates the cylinder in which the usual plunger 8 is mounted. The plunger carries 40 the mold table 8^a and impacts in the usual manner. In the bottom of the cylinder is a port 9 by means of which the fluid pressure is admitted into the cylinder to raise the plunger and exhausted out of the cylinder to permit the plunger to drop. Located in 45 the cylinder wall above the port 9 is an opening 10.

The controlling device comprises the casing 11 having a valve chamber 11^a, one end of which is in communication with the opening 10 by means of a connecting pipe 13, and the other end of which is in communication during the short period of ramming, with a source of constant air pressure through the pipe 12. The casing is provided with an inlet port 14 to which live pressure is conducted by means of the pipe 15; with a pair

of exhaust ports 16 and 16^a arranged in the same plane but on opposite sides of the casing; and with a port 9^a. At the respective ends of the casing are leakage ports 18 and 19 the purpose of which will hereinafter be described. The port 9 in the cylinder is connected with the ports 16^a and 9^a of the casing 11 by means of a pipe 9^b which is bifurcated at the casing end and which in effect substantially forms a continuation of the port 9.

Mounted within the casing is a valve 20, one end of which is connected with a piston 21 and the other end with a piston 22. The valve 20 controls the port 9^a and the exhaust ports 16 and 16^a. The leakage port 18 is so proportioned relative to the pipe 12 that the pressure is admitted to the casing faster than it flows out through the port 18 so that there is a constant head of pressure against the face of the piston 21. It will be apparent that a relatively small pressure on the piston 21 is required to shift the valve to the left inasmuch as the pressure from the pipe 15,— 80 which normally is preferably in the neighborhood of from 50 to 60 pounds—acts against both the valve 20 and the piston 21 equally.

The operation of the device is as follows: 85 The pressure against the face of the piston 21 moves the valve 20 to the left so as to cover the exhaust port 16 and the port 16^a and uncover the port 9^a, at which time pressure from the pipe 15 and port 14 flows through the port 9^a, pipe 9^b and port 9 into the bottom of the cylinder where it acts against the lower face of the plunger and raises the plunger. When the plunger has reached its raised or top position and uncovers the opening 10, the pressure in the cylinder flows through the opening 10 and connecting pipe 13 into the opposite end of the casing where it acts against the face of the piston 22 and shifts the valve to the right, uncovering the ports 16^a and 16 and covering the port 9^a. The air is thus exhausted from the cylinder via the port 9, pipe 9^b, port 16^a, exhaust port 16, and exhaust pipe 17. The plunger then falls by 105 the action of gravity. The pressure remaining in the chamber to the left of the piston 22 exhausts through the leakage port 19 and the pressure on the piston 21 again shifts the valve to the left and the operation is repeated. It will be apparent the cylinder pressure is sufficient to move the

valve to the right against the pressure on the piston 21, and that this action may be obtained by any one of a number of ways, such for example, in the manner just described in which the pressure in the pipe 12 is less than that in the main supply pipe 15, or in so proportioning the leakage ports that the cylinder pressure will not exhaust through the leakage port 19 as fast as live pressure exhausts through the leakage port 18. The operation is controlled by the valve 12^a in the pipe 12 which may also be used to throttle the pressure in the pipe 12 to any desired degree.

15 It will be obvious that the controlling device is automatic in operation upon the opening of the valve 12^a, and that it is simple in construction whereby the parts are not liable to get out of order.

20 In Fig. 3 I have shown the valve working in vertical position. In this case I prefer to bolt the casing 11 directly to the side of the cylinder and bifurcate the end of the port 9 so as to communicate directly with 25 the ports 9^a and 16^a without the provision of a connecting pipe such as 9^b shown in Fig. 2. In the construction of Fig. 3 the chamber of the valve casing extends above and below the port 9. The operation is the 30 same.

What I claim is:—

1. In combination with a jarring machine having a cylinder provided with a port therein and a plunger within said cylinder, 35 a valve casing connecting with said port the valve chamber of which extends on both sides of said port, and a valve in said casing for allowing the admission of operating fluid to said cylinder through said port for raising said plunger and adapted to be reversed by means of a piston at one end of and connected to said valve when said plunger has reached its raised position, thereby cutting off the admission of fluid to said 40 cylinder to allow the fluid therein to exhaust through said port and permit said plunger to drop in said cylinder.

2. In combination with a jarring machine having a cylinder provided with a port therein with an opening above the same and a plunger within said cylinder, a valve casing connecting with said port and said opening having a valve chamber extending on

each side of the port, and a valve in said casing for allowing the admission of operating fluid to said plunger through said port for raising said plunger and adapted to be reversed by means of a piston at one end of and connected to said valve when said plunger has reached its raised position, by the fluid passing through said opening, thereby cutting off the admission of fluid to said cylinder to allow the fluid therein to exhaust through said port and permit said plunger to drop in said cylinder.

3. In combination with a jarring machine having a cylinder provided with a port therein with an opening above said port and a plunger within said cylinder, a valve casing connecting with said port and opening having a valve chamber extending on each side of said port, and a valve within said casing having a piston connected to an end thereof, said valve allowing the admission of operating fluid to said cylinder through said port for raising said plunger and adapted to be reversed when said plunger has reached its raised position by the fluid passing through said opening and to one end of said piston, thereby cutting off the admission of fluid to said cylinder to allow the fluid therein to exhaust through said port and permit said plunger to drop in said cylinder.

4. In combination with a jarring machine having a cylinder provided with a port therein with an opening above said port and a plunger in said cylinder, a valve casing connecting with said port, and a valve in said casing for allowing the admission of operating fluid to said cylinder through said port for raising said plunger and adapted to be reversed by differential pressure when the plunger uncovers said opening on its upward stroke, thereby cutting off the admission of fluid to said cylinder to allow the fluid therein to exhaust through said port and permit said plunger to drop in said cylinder.

In testimony whereof I have hereunto signed my name in the presence of the two 100 subscribed witnesses.

EDGAR H. MUMFORD.

DISCLAIMER.

1,105,821.—*Edgar H. Mumford*, Plainfield, N. J. JOLT RAMMING-MACHINE. Patent dated August 4, 1914. Disclaimer filed December 29, 1914, by the patentee.

Enters this disclaimer—

“To claim 4 in said specification, which is in the following words, to wit:
“4. In combination with a jarring machine having a cylinder provided with a port therein with an opening above said port and a plunger in said cylinder, a valve casing connecting with said port, and a valve in said casing for allowing the admission of operating fluid to said cylinder through said port for raising said plunger and adapted to be reversed by differential pressure when the plunger uncovers said opening on its upward stroke, thereby cutting off the admission of fluid to said cylinder to allow the fluid therein to exhaust through said port and permit said plunger to drop in said cylinder.”
